UNITED STATES PATENT OFFICE.

WILLIAM BEARD, OF SALIDA, COLORADO.

INTERNAL-COMBUSTION ENGINE.

1,184,158.

Specification of Letters Patent. Patented May 23, 1916.

Application filed June 4, 1914. Serial No. 842,962.

To all whom it may concern:

Be it known that I, WILLIAM BEARD, a citizen of the United States, residing at Salida, in the county of Chaffee and State of Colorado, have invented certain new and useful Improvements in Internal-Combustion Engines; and I do declare the following to be a full, clear, and exact description of the invention, such as will enable others skilled in the art to which it appertains to make and use the same.

My invention relates to improvements in internal combustion engines and more particularly to those of the four cycle type.

The object of the invention is to provide simple means whereby a greater amount of mixture may be supplied to the various cylinders than the amount which they obtain by drawing in their own charges of mixture on the descent of their pistons.

In carrying out the above end, I provide the crank case of the motor with a number of air-tight compartments, provide each of said compartments with independent air intakes and air outlet valves, a manifold which leads from the air outlet valves to the intake manifold of the engine, said intake manifold discharging into the inlet valve cages as is common in devices of this character, and a spray nozzle projecting from a suitable carburetor into the air manifold.

With the above and minor objects in view, the invention resides in certain novel features of construction and combination herein described and claimed and shown in the drawings wherein:—

Figure 1 is a side elevation of an internal combustion motor constructed in accordance with the invention; Fig. 2 is a central vertical section of the motor; Fig. 3 is a view similar to Fig. 1 showing the carburetor, the air manifold, and the cages of the air-outlet valves in section; Figs. 4 and 5 are vertical transverse sections on the lines 4—4 and 5—5 of Fig. 1; Fig. 6 is a horizontal section taken substantially upon the line 6—6 of Fig. 4; Fig. 7 is a detail horizontal sectional view through the carburetor and taken on the line 7—7 of Fig. 3; Fig. 8 is a detail side elevation of a portion of the crank case, showing the manner in which the air intake and outlet valves may be mechanically operated; Figs. 9 and 10 are detail transverse sections taken upon the lines 9—9 and 10—10 of Fig. 8.

In the accompanying drawings, I have

shown my improved engine as comprising in general, a sectional crank case 1, a pair of transverse partitions 2 in the crank case, 60 independent air intake and air outlet valves 3 and 4 in to the compartments formed by the partitions, a plurality of cylinders 5, pistons 6 in the cylinders, a crank shaft 7, connections between the pistons and the 65 crank shaft, intake valves 8 into the upper ends of the cylinders, exhaust valves 9 therefrom, an inlet manifold 10, an air manifold 11 which communicates with the cages of the valves 4, an upright 70 tube 12 connecting the manifolds 10 and 11 and a carburetor 13 having a nozzle discharging into said tube 12. In addition to the elements so far briefly set forth, the invention contemplates certain other features 75 of construction and combination to be hereinafter described.

As above stated, the crank case 1 is of sectional formation, and its upper section carries the cages 14 and 15 for the air inlet 80 and outlet valves 3 and 4 respectively. These cages may be of any appropriate formation but are preferably so constructed as to allow the valves 3 and 4 to be automatically closed by means of suitable 85 springs. As clearly shown in Figs. 3 and 4, the cages 15 are here shown of cylindrical formation having their upper ends provided with outlet ports 16 which communicate with the interior of the air manifold 90 11, the latter being of suitable length and dimensions and having a boss 17 rising from its central portion and a similar boss 18 depending from its under side and directly beneath the boss 17. 95

The boss 17 is provided for the purpose of forming a proper connection between the air manifold and the above mentioned upright tube 12, the latter having its central portion contracted as at 19 for a purpose 100 to appear, the discharge nozzle 20 of the carburetor 13, being disposed at said contracted portion.

The pipe 12 is further provided with a bypass 21 which communicates freely with the 105 lower end of said pipe while its upper end communicates with the upper portion of said pipe through a spring closed valve 22. The pipe 12 is also provided with the usual butterfly valve 23 for controlling the 110 amount of mixture passing therethrough and into the cylinders. The inlet manifold 10 is of common construction as are likewise the cages for the valves 8 and 9. It is

expedient however that the valves 8 be operated by mechanical means, the necessity of this becoming apparent as the description proceeds.

5 The carbureter 13 may be of any suitable type for performing its functions, but it preferably includes an upright float chamber 24, a valve chamber 25 in communication therewith, a needle valve 26 in said chamber 25 and operated by an appropriate float 27 within the chamber 24, said valve automatically opening and closing a fuel inlet port in the lower end of the carbureter thereby allowing fuel to flow from a tank 28 through a valved outlet tube 29 and into the carbureter, when the float 27 lowers.

15 As clearly shown in Fig. 3, the discharge nozzle 20 of the carbureter extends upwardly within the contracted portion 19 of the pipe 12, the supply of fuel through said nozzle being cut off, when desired, by means of a needle valve 30 which is coarsely threaded through one side of an integral neck which connects the float chamber 24 with the tube or pipe 12. The outer end of the needle valve 30 passes revolvably through a stuffing box and is provided with an operating lever 31, the latter being limited in its outward movement by means of a stop 32 and carrying on its lower side, a short arm 33 which is connected by means of a link 34 to a lever 35 which is pivoted intermediate its ends to an arm which depends from a screw plug 36, the latter being threaded into the interior of a valve cage 37 which is rigidly secured to the boss 18. The plug 36 is provided with a central opening having its upper portion formed into a valve seat for the reception of a conical valve 38 from which a stem 39 depends and has a pivotal connection with the inner end of the lever 35. Thus it will be seen that when the arm 31 is rocked for the purpose of causing the needle valve 30 to close the outlet from the carbureter, the link 34 will push downwardly upon the outer end of the lever 35 thus causing its inner end to move upwardly to unseat the valve 38. If now, any leakage should occur through the nozzle 20, the fluid will be allowed to escape and will not accumulate in the air manifold 11.

20 In order that the needle valve 30 may be normally retracted until the arm 31 contacts with the stop 32, I preferably provide a light coil spring 40 and, for the purpose of actuating the arm 31, I employ a rather stiff spring 41 which may be operated in any suitable manner.

25 Coming now more particularly to details most clearly shown in Figs. 2 and 6, the crank case 1 is provided at its center, with an upstanding bearing post 42 which carries a suitable bearing 43 disposed in longitudinal alignment with bearings 44 carried

30 by the ends of the crank case. These bearings are of course provided for the reception of the crank shaft 7, the cranks 46 of which are here shown as standing in vertical alinement, the two central cranks being raised and the two endmost being lowered. By reference to these two figures, it will be seen that the partitions 2 divide the crank case 1 into a central compartment 47 and two endmost compartments 48 and that each compartment is provided with an air inlet valve and an air outlet valve of the forms before described.

35 With the parts as above described, (see Fig. 2) the operation of the device is as follows: The pistons I and IV on their descent, have forced a charge of air from the compartments 48 past the fuel spray nozzle 20 and into the cylinder above the piston I, this downward movement having been effected by expansion of the gases above the piston IV; the piston III, on its ascent, has scavenged its cylinder of burnt gases and the piston II has compressed a charge of mixture in its cylinder and now stands in position to have said charge ignited by the 40 sparking means. When said gas is ignited, above piston II, the pistons I and IV will move upwardly thus compressing the gas above the piston I and scavenging the cylinder of the piston IV; the pistons II and III, in moving down, force a charge of air from the compartment 47 past the fuel spray nozzle 20 and into the cylinder above the piston III which, upon its ascent, will compress said gas to be fired. Thus it will be seen that the two compartments 48 feed the two endmost cylinders and that the central compartment, equal in volume to the two compartments 48, feeds the two central cylinders and that this feeding occurs at proper intervals to force charges of mixture into the intake cylinders.

45 It is to be noted that by providing the above described connections between the needle valve 30 and the valve 38, the latter is automatically opened when the former is closed, thus preventing any fuel-accumulating within the air manifold 11 and the pipe 12. This mechanism also becomes advantageous when the motor is employed in connection with an automobile. In this connection, when the vehicle is running down grade, the above mentioned switch may be actuated to break the circuit of the sparking mechanism thereby automatically closing the needle valve 30 and opening the valve 38. As the pistons continue to operate, the air forced out of the crank case, is now free to pass upwardly into the cylinders of the 50 motor, thus effectually cooling the same. The valve 38 being now open, the air, discharged from the crank case, will flow through the opening normally closed by said valve, to a certain extent, thus blowing any 55

fuel which may have accumulated in the cage 37, entirely out.

It may here be further explained that the by-pass 21 and its valve 22 are provided for the purpose of regulating the amount of free air which is fed to the mixture before it enters the cylinder. For this purpose, I have provided a hollow screw 22' which yieldingly, through the action of a coil spring, holds the valve 22 normally seated. By regulating the screw 22', it will be seen that the amount of free air, fed to the mixture, may be varied.

In the figures of the drawings so far described, it will be seen that I have provided automatically operated valves for allowing the correct amount of air to pass into the crank case and to be discharged therefrom. In Figs. 8, 9 and 10 however, I have shown the manner in which I may well employ a cam shaft 50' for mechanically opening said valves. The air inlet valve in this case stands upright with its conical head 51 resting upon an appropriate seat formed in the lower side of a laterally projecting valve cage 52. The valve 51 is provided with a depending stem 53 which slides loosely through a boss 54, which latter is carried by the cage 52 and supported by means of integral arms 55. As clearly shown in Fig. 10, the lower end of the boss 54 is tapered inwardly for the reception of a packing ring 56, the latter being held in proper position upon the stem 53 by means of a sleeve 57 which has its lower end contracted and inclined downwardly from its periphery to its center while its upper end is provided with an annular flange 58.

When the parts are in normal position the lower end of the sleeve 57 is borne upwardly against the packing ring 56 by means of a coil spring 59 which is disposed between the flange 58 and a washer 60, the latter being threaded upon the lower end of the valve stem 53 and being locked in position thereon by means of a nut 61 which carries a flange on its lower end for coaction with a cam 62 carried by the shaft 50. Thus it will be seen that the valve 51 will be mechanically opened when the cam 62 rises and that the packing ring 56 will be held in contact with the stem 53 at all times, the tension of the spring 59 acting not only to close the valves but also to force the sleeve 57 upwardly against said packing ring, thus compensating for any wear on the latter. It is to be understood that the cam shaft 50 extends throughout the length of the casing and that the above described structure is duplicated at each air inlet from the interior of the crank case.

In Fig. 9, I have shown the manner of operating the air outlet valves. The con-

struction here is identical with the construction shown in Fig. 10 with the exception that the valve cage 52' is provided with a hood 52'' which communicates with the air manifold 11. As the remaining structure is identical with that illustrated in Fig. 10, I have employed the same reference numerals thereon and if a further explanation thereof is required, the description of said Fig. 10 may be referred to.

From the foregoing description, taken in connection with the accompanying drawings, the salient features of the invention will be readily understood and it will be seen that I have produced an internal combustion engine of comparatively simple construction which will be highly efficient in operation on account of the increased volume of explosive mixture which is fed to its cylinders.

I have described my invention with considerable minuteness and have set forth certain specific embodiments which may well be employed for carrying out the objects of the invention. I do not however wish to be limited to details of construction or to any minor details other than as set forth in the appended claim.

Having thus described my invention, what I claim as new and desire to secure by Letters Patent is:

A four-cycle internal combustion engine comprising a plurality of cylinders having independent intake valves adapted to open only when the cylinders are free of burnt gases, an intake manifold for supplying explosive mixture to said cylinders through the intake valves thereof when the latter are opened, a single tube projecting from said intake manifold, a fuel nozzle extending into said tube, an air manifold spaced from said intake manifold and communicating with said tube, a crank case with which the cylinders communicate at their inner ends, partitions across the crank case whereby to provide a number of compartments, an air intake valve and an air outlet valve for each compartment, casings for the air outlet valves discharging into the air manifold, and pistons in the cylinders movable inwardly and outwardly in pairs, whereby all of the air compressed by the descent of each pair of pistons may be forced past the fuel nozzle and into the cylinder whose intake valve is open.

In testimony whereof I have hereunto set my hand in presence of two subscribing witnesses.

WILLIAM BEARD.
